UNITED STATES PATENT OFFICE

WILLIAM J. BACON, OF MEMPHIS, TENNESSEE, ASSIGNOR TO MYRTLE M. BACON, OF MEMPHIS, TENNESSEE

RADIATOR COVER

Application filed June 4, 1928. Serial No. 282,852.

My said invention relates to a radiator cover, and it is an object of the same to provide a radiator cover which shall conform as nearly as possible to the structure of a fire-place in which there is a forced draft. This device may be set over any form of radiator for water or steam or a modified form may be arranged in front of a radiator set into a recess in a wall. Within the scope of my invention it may also be used over other sources of heat which are broadly the equivalents of a radiator, specific terms being used in the claims for purposes of description rather than limitation. It has been found from actual experience that the best results are obtained with a casing having a mesh wire strainer covering an opening in the lower part of the front wall of the casing and another mesh wire strainer covering an opening in the upper part of said wall, the entire casing being preferably insulated, except at the openings, to prevent radiation which tends to set up a secondary circulation of air. It will be understood that if the air adjacent the outer walls of the casing is heated by radiation it will create a circulation such as will carry up dust from the floor without passing through the casing itself whereby the dust can be removed from the air by the screens and also by reason of the changes of direction in the travel of the air through the casing.

It is an object of my invention to provide a casing in which the air shall change direction preferably three times; i. e., it passes in approximately horizontally, then rises and then passes out approximately horizontally. In this movement the air current strikes against solid surfaces that help to cause particles of dirt in the air to be separated out of the same. Even in passing through the air screens or filters the current is not at right-angles to the filter and the impingement of particles of dirt against the screen at an angle

to the same helps to separate the dirt therefrom.

Another object of the invention is to prevent the formation of a pocket of air at the top of the radiator and for this purpose I provide an inclined plate rising from the rear of the casing toward the front to direct the current through the upper opening whether or not the same is provided with a screen.

Another object is to provide a forced draft. For this purpose I provide a smaller opening at the top of the casing than that at the bottom, which accelerates the passage of air out from the radiator, creating a draft along the floor and throwing the heated air out into the room away from the wall. By this means the room is heated more quickly than would otherwise be the case. For this purpose also I provide horizontal inwardly curved surfaces at the front and back of the casing which create a throat in the radiator cover for accelerating the movement of air through the radiator. It has been found by experiment that if the outlet is smaller than the inlet the air will pass out with a greater speed and it is intended to provide a device which shall speed up the circulation of air in the middle of the room rather than merely along the walls and the ceiling.

Referring to the drawings, which are made a part of this application and in which similar reference characters indicate similar parts:

Fig. 1 is a perspective of my improved device,

Fig. 2, a transverse, vertical section of the same, and

Fig. 3, a perspective of a modified form.

In the drawings reference numeral 10 indicates a radiator of any conventional or desired type with which my improved radiator casing may be used. The casing has a rear wall 11 with a longitudinal inward curved portion 12, a flat top 13, ends 14 and 15 and a

front wall 16 having a horizontal curved portion 17. The front, rear and side walls are insulated as indicated at 18 and an inclined plate 19 above the top of the radiator or other heating device is also insulated, this plate being for the purpose of throwing the air current forward and preventing the formation of a pocket of stationary air in the upper right-hand corner of the casing, as shown in Fig. 2. Air filters 20 and 21 are shown for the respective small upper and large lower openings at the front of the casing. These air filters may, as here indicated, be of wire mesh or of other suitable character. A water pan 22 is illustrated underneath the radiator, this water pan being intended to moisten the air in its passage through the casing. A suitable trough for filling the water pan is indicated in Fig. 1 at 23.

20 The operation of the device will be understood, it is thought, from the previous description. The air is drawn into the opening 21 along the floor and contacts with the heating surfaces of the radiator after which it passes out through the upper opening 20 with considerable force owing to the relative size of the openings and the narrow throat between the parts 12 and 17. The cold air moves along the floor and the hot air is ejected toward the middle of the room instead of merely passing up close to the wall. The particles of dirt in the air will strike against the rear wall or the inclined plate or the air filters, if such are used and at least a considerable part thereof will fall to the bottom of the casing instead of circulating around the room again and again.

Fig. 3 shows a form of my invention generally similar to that just described, the parts 12', 13', 14', 17' and 20' being similar in all respects, or in any desired respects, to those previously described. In this form of the invention, however, four legs 24 are provided, one of which is not shown, and the air may enter the casing at the bottom thereof on all sides or on so many as are left open, passing then through the throat and out through the air filter, if such is provided. Preferably also an inclined plate such as 18 will be provided in this form of the invention.

It will be obvious to those skilled in the art that various modifications may be made in my device without departing from the spirit of the invention and therefore I do not limit myself to what is shown in the drawings and described in the specification but only as indicated in the appended claims.

Having thus fully described my said invention what I claim as new and desire to secure by Letters Patent, is:

1. In combination with a radiator, a casing completely covering the radiator and having an upper and a lower opening in its front wall, the upper opening being smaller than the lower and the openings being respectively

adjacent the upper and lower ends of the radiator, and horizontal inward curves on the front and rear walls between said openings providing a throat for the cover.

2. In combination with a source of heat, a 70 casing having an outlet opening in its front wall, an inlet opening lower than the outlet and of larger capacity, and means between the openings forming a constricted throat for the casing.

In testimony whereof I affix my signature.

WILLIAM J. BACON.
